QUARTZ-TO-METAL SEAL

BACKGROUND OF THE INVENTION

1. Field of the Invention

This invention relates generally to seals of metallic lead-in conductors in essentially fused silica or quartz for electrical devices comprising a sealed envelope containing electric energy translation means to which electric current is supplied through the lead-in conductors. It further relates to a novel glass composition for forming a molten seal between the quartz and a portion of the lead-in conductor enclosed thereby.

2. Description of the Prior Art

By way of example only, the invention will be referred to especially in connection with so-called tungsten halogen lamps which comprise an envelope, usually of essentially fused silica, containing a tungsten filament and an inert gas filling along with a small amount of halogen such as iodine or bromine and which serves as a regenerative getter which returns to the filament tungsten particles vaporized therefrom during operation of the lamp. The filament is connected at its ends to lead-in conductors which may be sealed through respective pinch seal portions at opposite ends of a lamp or through a single pinch seal at one end of the lamp. The lead-in conductors each generally include a very thin foil portion of molybdenum which is hermetically sealed in the pinch seal, and an outer lead wire portion of refractory metal which is generally also molybdenum and which is attached at one end to the foil portion and extends through the pinch seal to the exterior thereof. While the molybdenum foil forms a hermetic seal with the quartz because of the extreme thinness and resilience of the foil, the relatively heavy outer lead wire is not hermetically sealed because of its relatively large diameter and the difference in coefficient of expansion between the quartz and the molybdenum. For that reason, and also because the formation of the pinch seal does not permit the quartz to flow completely around and against the full periphery of the outer lead wire, slight capillary passages are left between the quartz and the portion of the outer lead wire enclosed thereby. The thin foil is thus exposed to atmospheric oxygen entering by way of the capillary passages whereby oxidation of the foil at elevated temperatures above about 350° C. results in breakage of the electrical connection to the outer lead wire.

It has been found heretofore that the life of such seals could be materially increased in the elevated temperature range of about 500° to 800° C. by using outer lead wires consisting, at least at their surface, of platinum, and by filling the capillary passages around those wires with a lead borate composition which is molten at such temperature so that it forms a liquid seal against the entrance of atmospheric oxygen during operation of the lamps. The lead borate attacks and corrodes molybdenum, thereby necessitating the use of platinum or platinum-clad outer lead wires. Also, the lead borate does not melt and run sufficiently at temperatures below about 500° C. to be fully useful in the lower range of about 350° to 500° C.

SUMMARY OF THE INVENTION

Accordingly, it is an object of this invention to provide improved protection for seals of the type described, particularly in the temperature range of about 350° to at least 725° C. for relatively long lamp lives. It is a further object to provide a molten seal material which is compatible with molybdenum and which will therefore afford a significant cost reduction.

In accordance with the invention, we have discovered that the above objectives are attained with a novel glass composition which affords a molten seal protection in the stated temperature range and which consists of a low melting antimony borate glass. We have found that further substantial improvement is obtained by incorporating in the glass a small amount of molybdenum trioxide or tungsten trioxide. Further features and advantages of the invention will appear from the following detailed description.

BRIEF DESCRIPTION OF THE DRAWING

In the drawing,

FIG. 1 is a fragmentary elevation of one end of a double-ended type of lamp embodying the invention;

FIG. 2 is a longitudinal section, on an enlarged scale and along the line 2-2 of FIG. 3, which more clearly illustrates the seal in accordance with the invention;

FIG. 3 is a transverse section, also on an enlarged scale and along the line 3-3 of FIG. 2, and which also illustrates more clearly the seal according to the invention;

FIG. 4 is an elevation of a single-ended type lamp embodying the invention; and

FIG. 5 is a ternary chart showing variations in glass composition.

DESCRIPTION OF THE PREFERRED EMBODIMENTS

Referring to FIG. 1 of the drawing, the lamp illustrated therein may be, for example, of the tungsten-halogen type comprising a tubular envelope 1 consisting essentially of fused silica which may be fused quartz or the product known as 96 percent silica glass and sold under the name Vycor. A helically coiled tungsten filament 2 extends axially of the envelope and is suitably connected at its ends to lead-in conductors 3 which are sealed through respective flattened press or pinch seal portions 4 at opposite ends of the envelope. The envelope 1 is filled with an inert gas such as nitrogen, argon, krypton or xenon or mixtures thereof, and a small quantity of halogen such as iodine or bromine and which serves as a regenerative getter by combining with tungsten vaporized from the filament onto the envelope wall to form a compound containing the tungsten and halogen and which returns to the vicinity of the filament 2 where it is broken down and the tungsten is redeposited onto the filament and the halogen is free to return to the envelope wall to repeat the cycle.

The actual hermetic seal between the quartz seal portion 4 and the lead-in conductor 3 is at an extremely thin ribbon or foil portion 5, preferably of molybdenum. An outer lead wire portion 6 and an inner lead wire portion 7 are welded to respective ends of the foil 5. When the lamp is of the halogen cycle type, the inner lead wire 7 is preferably made of tungsten, and the outer lead wire 6 is also made of refractory metal, preferably molybdenum.

Because of the difference in coefficient of expansion of the quartz and the relatively heavy outer lead wire portion 6, and also the manner of compressing the quartz to form the pinch seal 4, there is a slight capillary passage or passages 8 between the quartz and the part of the outer lead portion 6 enclosed therein, through which atmospheric oxygen can reach the outer end of the foil portion 5 which results in oxidation and breaking of the connection between the molybdenum foil 5 and the outer lead wire 6 at temperatures above about 350° C.

In accordance with the invention, seal life is materially increased, especially in the temperature range between about 350° C. to at least 725° C., by filling the capillary passages 8 with a low melting antimony borate glass, preferably containing a small amount of molybdenum or tungsten trioxide and illustrated at 9. Such a glass can be made to melt and flow at

relatively low temperatures so that it forms a molten seal at elevated temperatures at which molybdenum would be oxidized. The molybdenum or tungsten trioxide additive to the glass promotes wetting to the molybdenum lead wire, and it also serves to stabilize the glass. Moreover, the antimony borate glass does not attack the molybdenum outer lead wire 6 and foil 5 whereas lead borate compositions would attack the molybdenum lead 6 and must be kept away from the foil 5. The antimony borate glass also does not attack nickel which is used in some lamps as a fuse wire attached to the molybdenum lead wire at a point very close to the seal, as in U.S. Pat. No. 3,346,768 to G. F. Patsch.

A preferred method of introducing the antimony borate glass 9 into the passages 8, which may have a width of the order of a thousandth of an inch, is illustrated in FIG. 1. A small ring or bead 10 of the antimony borate glass composi-

tion is slipped over the end of the outer lead wire 6 and onto the end of the quartz seal portion 4. Heat is then applied to the surface of the pinch seal 4, preferably by a small oxyhydrogen flame applied locally to the area enclosing the outer lead wire 6, to cause the bead 10 to melt and be drawn into the capillary spaces or passages 8.

A preferred composition for the glass 9 which has given particularly good results is, by weight, 65 percent Sb_2O_3 , 30 percent B_2O_3 and 5 percent MoO_3 . Such a composition may be prepared from a batch composed of, or corresponding proportionately to, 65 grams Sb_2O_3 , 53.3 grams H_3BO_3 and 5.0 grams MoO_3 . The mixture of finely divided batch ingredients may be heated in a platinum crucible or other suitable container in air at about $800^\circ C.$ until molten homogeneous glass is formed. It may then be quenched, for example between water-cooled steel rolls, to form a powder from which the beads 10 are formed. Alternatively, the molten glass may be drawn into rod form and applied in that form by holding one end of a length of the rod against the outer lead wire 6 where it emerges from the heated quartz pinch seal 4 to thereby melt the end of the rod and draw the molten glass into the capillary passages 8.

Some physical properties of this preferred antimony molybdenum borate composition are: softening point, $350^\circ C.$; density, 3.52 grams/cc.; and thermal expansion coefficient ($0^\circ - 300^\circ C.$), $100 \pm 10 \times 10^{-7}/^\circ C.$

The single-ended type of lamp shown in FIG. 4 comprises a fused silica or quartz bulb 12 containing a helically coiled-coil tungsten filament 13 which extends transversely of the bulb axis and has helically single-coiled leg portions 14 which extend generally longitudinally of the envelope into a flattened pinch seal 15 at the end of the envelope. The outer ends of the filament leg portions 14, within the pinch seal 15, are connected to respective lead-in conductors preferably comprising a molybdenum foil portion 16 which is hermetically sealed in the pinch 15 and an outer lead wire 17 preferably of molybdenum and extending exteriorly of the pinch seal. The filament leg 14 is welded to the foil 16 and, for ease of welding, a short length of tungsten spud wire 18 is preferably provided in the interior of the leg portion 14 within the pinch seal.

As in the lamp of FIGS. 1-3, there are fine capillary passages around the portions of outer leads 17 embedded in the pinch 15, corresponding to passages 8 in FIGS. 2 and 3, and which are filled with the antimony borate glass as shown at 9 in said FIGS. 2 and 3.

The bulb may be filled with an inert gas such as nitrogen and a small quantity of halogen such as hydrogen bromide. An overwind coil 19 is preferably slipped over the ends of the filament legs 14 for reasons fully disclosed in U.S. Pat. No. 3,470,410 to G. F. Patsch. The lamp may be completed by cementing onto the pinch seal 15 a rectangular base (not shown) of refractory insulating material and having contact pins projecting from the bottom thereof and electrically connected to respective outer lead wires 7.

Testing of standard lamps with the application of the antimony borate glass indicates substantial decrease in lead wire oxidation and significant increase in lamp life. In the case of a single-ended type of halogen cycle lamp of very high compactness and high intensity, such as that shown in FIG. 4 and used for photographic purposes as a floodlight with movie cameras, designated in the industry by the code letters DVY, and rated at 650 watts on a 120 volt supply, seal temperatures during operation in a reflector are in the order of 550° to $575^\circ C.$ Two series of 15 lamps each were operated to termination of life with no seal failures using the preferred antimony molybdenum borate glass seals. Comparable testing indicated 100 percent failures before rated life of 25 hours without this protection.

In another test of 2000 watt studio lamps of single-ended design having a coiled-coil filament extending axially of a 1 inch diameter envelope and operated in conventional fixtures, the standard lamps failed in approximately 25 to 50 hours. The same type of lamps containing the molten seal antimony molybdenum borate glass had an average life exceeding the

rated 500 hours life with several lamps burning in excess of 700 hours.

Further testing indicated that even without the 5 percent addition of molybdenum trioxide, the basic antimony borate glasses are effective in increasing seal life, although not as fully effective as those containing the molybdenum.

In general, we have found that glasses similar to the preferred composition described above are those contained within the area A bounded by the solid line 20 of the ternary diagram shown in FIG. 5. Compositions outside area A form much poorer glasses and some of them are completely or partially crystalline or otherwise unsuitable. However, minor additions of other glass-forming oxides, modifiers or alkalies may be made in the glasses in area A without substantially changing the composition or altering the effectiveness of the glass in accordance with the invention. Also as indicated above, tungsten trioxide has been substituted for molybdenum trioxide to make satisfactory glasses.

Basic binary antimony borate glasses have been made with compositions indicated by the dots along the right-hand boundary of the FIG. 5 diagram. Those glasses possess the desirable properties of low softening point and relative inertness with respect to molybdenum and nickel. Other dots within area A indicate ternary compositions which are preferred because of enhanced wetting of the molybdenum lead wire and improved stability. Still other dots outside area A indicate compositions which are unsuitable.

The preferred antimony molybdenum borate compositions 30 are those within area A of FIG. 5 when bounded by the solid line 20 as foreshortened by the broken line 21 within the right-hand boundary and which represents a minimum molybdenum content of about 2.5 percent by weight. The single preferred composition of 65 percent Sb_2O_3 , 30 percent B_2O_3 and 5 percent MoO_3 is indicated by the dot 22.

Ternary compositions which have been prepared and are shown by the dots within area A of FIG. 5 have the following compositions in percent by weight:

	Sb_2O_3	B_2O_3	MoO_3
40	55	35	10
	60	25	15
	61.60	28.40	10.00
	63.30	29.20	7.50
45	65.00	15.00	20.00
	65.00	30.00	5.00
	66.70	30.80	2.50
	70.00	15.00	15.00
	75.00	15.00	10.00

The binary compositions indicated by dots along the right-hand boundary of FIG. 5 are as follows:

	Sb_2O_3	B_2O_3
50	90.70	9.29
	86.26	13.74
	80.72	19.28
55	73.63	26.37
	68.40	31.60
	64.22	35.78
	51.15	48.86

Ternary compositions of antimony tungsten borates were prepared with proportions as follows:

	Sb_2O_3	B_2O_3	WO_3
60	63.00	29.10	7.90
	65.00	30.00	5.00
65	61.50	28.50	10.00
	58.20	26.80	15.00
	55.00	25.00	20.00
	51.30	23.70	25.00

What we claim as new and desire to secure by Letters 70 Patent of the United States is:

We claim:

1. A seal for electrical devices comprising a member of essentially fused silica and a lead-in conductor sealed in and extending through said member, said conductor including an intermediate thin foil portion of molybdenum hermetically

sealed within said member and subject to oxidation at elevated temperatures above about 350° C., and an outer lead wire portion of refractory metal connected to and extending from said foil portion through said silica member to the exterior thereof with a slight capillary passage between the silica member and the part of said outer lead wire enclosed thereby, and a filling in said passage of low melting antimony borate glass having a composition within the area A bounded by the solid line 20 in the FIG. 5 chart, said glass forming, at elevated temperatures, a molten seal which prevents ingress of atmospheric oxygen to said molybdenum foil portion.

2. A seal as in claim 1 wherein the glass within area A is bounded exclusively by the solid line 20 as foreshortened by the broken line 21.

3. A seal as in claim 2 wherein the outer lead wire portion is composed of molybdenum.

4. A seal as in claim 1 wherein the said glass is of a composition consisting essentially, by weight, of approximately 65 percent Sb_2O_3 , 30 percent B_2O_3 and 5 percent MoO_3 .

5. A seal as in claim 4 wherein the outer lead wire portion is composed of molybdenum.
